ABSTRACT

A cosmetic composition for treating hair comprising an electrophile methylol amine and a urein compound, one or both of which contain a chemical group which has cosmetic properties; and a method of treating hair with this composition.

The compounds having the formula:

in which $n = 1$ or 2, X is O, S or NH and Y is a disulfide, carboxylic acid, tertiary or quaternary amine or —SH group which has cosmetic properties.

6 Claims, No Drawings

COSMETIC COMPOSITION FOR TREATING HAIR

This invention relates to a cosmetic composition which makes it possible to improve the condition of human hair and to impart thereto certain properties which are useful when it is to be subjected to a subsequent cosmetic treatment.

It is known that hair is more or less degraded by atmospheric agents such as sea water, or the sun, or as a consequence of chemical treatments such as permanent waves and bleachings.

The effects of such degradations may be to a large extent eliminated by using the compositions according to the invention.

It has already been suggested, in order to improve the strength and elasticity of the hair, that it be treated with compositions containing dimethylolurea or dimethylolthiourea so as to obtain the desired result by polymerization and condensation of these active compounds on the keratin in the presence of an acid catalyst, under the influence of heat.

It has likewise been suggested that compositions comprising methylol products which are more stable than dimethylolurea and dimethylolthiourea be used, which products yield excellent results due to polymerization in the keratin chain and condensation of these compounds on the reactive groups of the keratin, thereby in practice imparting to the treated hair greater strength, an improved appearance and, in general, attractive cosmetic properties.

It is also known that it is desirable, to not only strengthen the keratinic fiber by means of the above process, but also to impart thereto a greater capacity to react with various products used in the cosmetic treatment of hair.

In particular, it has been found desirable to attach inside the hair compounds having disulfide bonds. These additional S-S bonds result in a new and valuable behavior of the fiber with respect to chemicals conventionally used in the treatment thereof, such as reducing solutions containing mercaptans or sulfites, and oxidizing agents containing hydrogen peroxide, for example.

In like manner, attempts have been made to attach carboxylic groups inside the hair. This addition of acid groups increases the affinity of the fiber for basic dyes.

On the other hand, basic groups, or even fatty chains, have been introduced into the hair in order to increase the affinity of the hair for acid dyes, or durably improve the sheen and "feel" of the hair.

This list is by no means exhaustive and the number of cosmetic substituents or additives which it may be desirable to attach to the keratin of the hair is quite long.

Applicants have found that, in a surprising manner, the polycondensation of methylol compounds in the presence of compounds of the urein type leads to a compound or mixture of compounds having a rather high molecular weight containing the skeletons of both the methylol and urein compounds.

This phenomenon is particularly valuable when the compound of the urein type contains a cosmetic component attached to the nitrogen which is finally embedded inside the hair when the methylol compounds are polymerized in the keratin in the presence of these particular urein compounds.

This makes it possible to introduce into the hair reactive groups which are cosmetically valuable in that they strengthen the hair and particularly improve its mechanochemical properties after the polycondensation.

It is the object of the present invention to provide a composition for treating or modifying keratinic fibers essentially characterized by the fact that it comprises in combination at least one methylol compound comprising

at least one group responding to the formula:

in which:

R represents either hydrogen, a lower alkyl radical, a hydroxymethyl radical, or an alkoxyethyl radical,

R' represents either hydrogen, or a lower alkyl radical,

70

75

E represents a radical which is sufficiently electrophile to assure that the entire group is sufficiently chemically stable to prevent the immediate release of a formal molecule, and at least one urein compound responding to the following formula:

in which:

n=1 or 2

X represents oxygen, sulfur, or an NH radical,

Y represents hydrogen, or a monovalent or divalent organic radical depending on whether n=1 or 2.

the radical Y of the urea compound and or the methylol compound comprises a chemical function permitting it to serve a cosmetic purpose selected from the group consisting of a disulfide function, a carboxylic acid function, a tertiary or quaternary amine function, a fatty chain or an -SH function.

In a preferred embodiment of the invention, E is selected from among the following groups:

Among the methylol groups which may be used in the composition according to the invention are:

monomethylolurea, responding to the formula:

dimethylolurea, responding to the formula:

monomethylolthiourea, responding to the formula:

dimethylolthiourea, responding to the formula:

monomethylol dicyandiamide, responding to the formula:

trimethylol melamine, responding to the formula:

N,N-methyl, methylolurea, responding to the formula:

N,N-dimethylolurea, responding to the formula:

bis-methoxymethylurea, responding to the formula:

dimethylolethylene urea, responding to the formula:

dimethylolethylene thiourea, responding to the formula:

methoxymethyl dicyandiamide, responding to the formula:

dimethylol dihydroxy ethylene-urea

N,N'-(dimethylol dicarbamyl) cystamine, responding to the formula:

(diethyl, methyl, monomethylolethylurea)-ammonium iodide:

Among the urein-type compounds which may be used in the cosmetic compositions according to the invention are:

hydantoic acid, responding to the formula:

thiourea, responding to the formula:

5 N-methyl-dipropylurea, responding to the formula:

15 (dimethyl-copra-ethylurea)-ammonium chloride responding to the formula:

25 N,N'-carbamyl cystamine, responding to the formula:

compound responding to the formula:

compound responding to the formula:

N-carbamyl cysteamine, responding to the formula:

N-carbamyl cystamine hydrochloride responding to the formula:

55 N,N'-(dimethyl-ethylurea) cystamine dichloride:

(diethyl-methyl-ethylurea)-ammonium iodide responding to the formula:

diethylamino ethylurea, responding to the formula:

(dimethyl-dipropylurea)-ammonium methosulfate responding to the formula:

The composition according to the invention may advantageously contain from 0.5 to 12 percent and preferably from 1 to 4 percent by weight of methylol compounds.

In a preferred embodiment of the invention the number of urea groups carried by the urein-type compound lies between 0.2 and 3 times and preferably from 0.5 to 1.0 times the number of hydroxymethyl or alkoxy methyl groups carried by the methylol compound.

In one specific embodiment of the invention, the composition also contains an acid catalyst, which may be a mineral or organic acid used in the cosmetic field or a salt having an acid reaction.

The composition according to the invention may take the form of an aqueous or hydroalcoholic solution and serve as a setting lotion which may comprise any additives conventionally included in such lotions.

The composition according to the invention may also take the form of a gel or cream, or be packaged in aerosol form.

The composition according to the invention may also contain any ingredients conventionally used in cosmetics, such as dyes, perfumes, surface-active agents, swelling agents, resins, etc.

In one specific embodiment of the invention, the composition may be packaged in two phases, a solid phase containing the methylol compounds, and the urein-type compounds, and a liquid phase which is an aqueous or hydroalcoholic solution, which may contain conventional cosmetic additives and/or an acid catalyst.

In another version of this method of packaging this product, the solid phase contains only the methylol compounds, and the urein-type compounds are in aqueous or hydroalcoholic solution.

In this embodiment, the cosmetic composition according to the invention is prepared at the moment of use by dissolving the solid phase in the liquid phase. This method of packaging makes it possible to avoid the premature polycondensations which may take place during prolonged storage of the composition.

In particular, the solid phase or the aqueous phase of the cosmetic composition packaged in this manner may also contain a salt of sulfurous acid, such as sodium metabisulfite.

A further object of the present invention is to provide a method of treating hair characterized by the fact that the hair is impregnated with the above-described composition, and then dried by heating, after having first been rinsed.

In a first method of carrying out this process, the cosmetic composition does not itself contain the acid catalyst necessary to bring about polycondensation of the methylol compounds and the urein-type compounds in the keratinic fiber, and this acid catalyst is instead applied to the hair either before or after the composition according to the invention.

In another method of carrying out this process a cosmetic composition which already contains the acid polymerization catalyst is directly applied to the hair, which is then dried as has already been described.

The treatment of the hair with the composition according to the invention leads to two results. On the one hand, it

strengthens the keratinic fiber by forming a polymer inside that fiber and, on the other hand, permits the introduction and attachment of reactive groups inside the keratinic fiber. These reactive groups advantageously modify the reactivity of the keratin with respect to other cosmetic reagents.

It is a further object of the present invention to provide the new article of manufacture which consists of a compound responding to the following formula:

10

in which:

15 $n = 1 \text{ or } 2,$

X represents hydrogen, sulfur, or an $-\text{NH}$ radical, Y is a radical comprising a chemical function which enables it to serve a cosmetic purpose, such, for example, as a disulfide function, a carboxylic acid function, a tertiary or quaternary amine function, a fatty chain, or an $-\text{SH}$ function.

The present invention has as its particular object the production of a new article of manufacture consisting of a compound selected from the group consisting of:

20 25 N -methyl-dipropylurea, (dimethyl-copra-ethylurea)-ammonium chloride, N,N' -carbamyl cystamine, N -carbamyl-cystamine hydrochloride, N,N' -(dimethyl-ethylurea)-cystamine dichloride, (diethyl-methyl-ethylurea)-ammonium iodide, diethylamino ethylurea (dimethyl-dipropylurea)-ammonium methosulfate, and N -carbamyl cysteamine.

25 30 A further object of the present invention is to provide a new method of preparing urein-type compounds as described above, characterized by the fact that a cyanate or an alkaline thiocyanate is reacted with amine compounds having a Y -group representing the cosmetic additive in question attached to the nitrogen.

35 40 In a particular method of carrying out the invention, the amine which carries the cosmetic additive attached to its nitrogen atom is reacted with urea, to produce the corresponding urein by elimination of ammonia.

45 In another method of carrying out the invention, a tertiary amine having a cosmetic additive attached to its nitrogen atom is reacted with a halogenoalkylurea.

50 55 In order that the invention may be better understood, several examples of the use of compositions according to the invention will now be described, purely by way of illustration.

EXAMPLE 1

50 An aqueous solution of the following composition is applied to natural hair which has first been washed and dried:

monomethylolurea	3.6 g.
hydantoic acid	1.18 g.
water, q.s.p.	100 cc.

55 The hair is then set in a conventional manner by winding it up on rollers and drying it under a hood at a temperature of 45°-50°C. This attaches to the keratin of the hair an acid compound having the following statistical formula:

60 65 in which:

n lies between 2 and 3 inclusive.

Hair treated in this manner has a greater affinity for basic dyes than natural, or untreated hair. It is also strengthened and the set holds well and is springy.

EXAMPLE 2

70 75 A solution of the following composition is applied to hair which has been bleached:

monomethylolurea	1.8 g.
N,N'-carbamyl cystamine	1.8 g.
phosphoric acid, q.s.p., pH 2.5	
water, q.s.p.	100 cc.

The hair is then set in a conventional manner by keeping it wound up on rollers for 30 minutes at a temperature between 45° and 50° C.

This operation permits the attachment to the keratin of a compound of the disulfide type which is soluble in reducing media and has substantially the following composition:

In this formula:

n lies between 0.5 and 1 inclusive.

The hair is strengthened and the set holds well and is springy.

Moreover, the presence of artificial disulfide bonds in the keratinic fiber makes it possible to subsequently permanently wave or bleach the hair under improved conditions.

EXAMPLE 3

Natural hair which has first been washed and dried is treated with a solution having the following composition:

monomethylolurea	3.6 g.
N-methyl-dipropylurea	2.3 g.
hydrochloric acid, q.s.p., pH 2.5	
water, q.s.p.	100 cc.

The hair is then set in a conventional manner, keeping it for about 30 minutes at a temperature between 45° and 50° C.

This procedure leads to the attachment of a cationic condensate to the keratinic fiber which has the advantage that it may thereafter be very easily removed by simple shampooing.

On the other hand, the hair has been strengthened and the "set" is of excellent quality.

EXAMPLE 4

In the case of hair which has previously been bleached, and which is now to be permanently waved, the hair is first impregnated with the following composition:

monomethylolurea (dimethyl-copra-ethylurea)-ammonium chloride	8 g.
acetic acid q.s.p., pH 3	2 g.
water q.s.p.	100 cc.

The hair is then kept for about 30 minutes under a current of hot air at a temperature between 40° and 45° C. An attractive permanent may then be obtained in a conventional manner.

Because of the intermediate treatment, the resulting permanent is of excellent quality with respect to springiness and the length of time the wave lasts, and the appearance, sheen and "feel" of the hair is improved by the attachment of a fatty chain to the keratin.

EXAMPLE 5

Preparation of (dimethyl-dipropylurea)-ammonium methosulfate

The first step is to prepare N-methyl-dipropylurea by reacting potassium cyanate with N-methyl-dipropylamine dihydrochloride in stoichiometric proportions. The reaction is carried out in aqueous solution at a temperature of 90° C. for 2 hours.

The product is dried by evaporation and then extracted with hot absolute ethanol. The result is a white powder titrating 95%

7

percent of the theoretical amount of total amines and of tertiary amines.

One mol of N-methyl-dipropylurea is suspended in 1 liter of absolute ethanol. A stoichiometric quantity, or a slight excess, of methyl sulfate is added slowly, while stirring. The resulting quaternary compound separates from the alcoholic layer, in the form of a thick oil which is vacuum dried and may be purified by washing with ether. The yield is practically quantitative.

10

8

EXAMPLE 6

Preparation of N,N'-(dimethyl-ethylurea)-cystamine dichloride

15 One mol of chloroethylurea is prepared in a conventional manner by reacting potassium cyanate with chloroethylamine hydrochloride, and then dissolving the product in ethanol at 70° C. 0.5 mol of tetramethyl cystamine, prepared by alkaline hydrolysis of the reaction product of sodium thiosulfate and β -bromo-diethylamino ethane hydrobromide is then added. The mixture is heated for 3 hours and 30 minutes, at 85° C., and the solvent then evacuated under vacuum. The product is dried on phosphoric anhydride. The resulting paste is washed with 450 cc. of chloroform, and again dried on phosphoric anhydride. The final result is a 98 percent yield of a solid white product titrating about 90 percent of the theoretical value of disulfide and ionized chloride.

20 What is claimed is:

25 1. A process for treating human hair which comprises applying to said hair a composition containing in a solvent selected from the group consisting of water and hydroalcoholic solution:

1. at least one compound selected from the group consisting of monomethylolurea, dimethylolurea, monomethylol thiourea, dimethylol thiourea, monomethylol dicyandiamide, trimethylol melamine, bismethoxymethyl urea, dimethylol ethylene urea, dimethylol ethylene thiourea, methoxymethyl dicyandiamide, dimethylol dihydroxy ethylene urea, N,N'-(dimethylol dicarbamyl) cystamine, (diethylmethylmonomethylol ethylurea)-ammonium iodide, N,N-methylolurea and N,N-dimethylolurea, and 2. at least a urein compound corresponding to the formula:

35

in which:

X is selected from the group consisting of O, S and NH, n is 1 or 2 and when n is 1, Y is selected from the group consisting of hydrogen,

45 50 55 60 65 70 75 80 85 90 95

and when n is 2, Y is selected from the group consisting of

said composition containing said compound (1) in a concentration ranging from 0.5 to 12 percent by weight, polycondensing said compound and said urein compound on said hair in the presence of an acid catalyst in amounts sufficient to polycondense said compound and said urein compound, rinsing the hair and then drying the same.

2. The process of claim 1 wherein said acid catalyst is selected from the group consisting of acetic acid, phosphoric acid and hydrochloric acid.

3. The process of claim 1 wherein said acid catalyst is applied to the hair prior to the application of said composition to the hair.

4. The process of claim 1 wherein said acid catalyst is applied to the hair subsequent to the application of said composition to the hair but before rinsing said hair.

5. The process of claim 1 wherein said acid catalyst is applied to the hair concurrently with the application of said composition to the hair.

6. The process of claim 1 wherein said urein compound is

selected from the group consisting of hydantoic acid, thiourea, N-methyl-dipropyl urea, (dimethyl-copra-ethylurea)-ammonium chloride, N,N'-carbamyl cystamine, a compound having the formula

a compound having the formula

N-carbamyl cysteamine, N-carbamyl cystamine hydrochloride, N,N'-(dimethyl-ethylurea)cystamine dichloride, (diethyl-methyl-ethylurea)-ammonium iodide, diethylamino ethylurea and (dimethyl-dipropylurea)-ammonium methosulfate.
